UNITED STATES PATENT OFFICE.

CHARLES BURTON, OF PADDINGTON, AND REGINALD ALBERT SHAW, OF ROSEVILLE,
NEW SOUTH WALES, AUSTRALIA.

FOLDING BED.

1,360,983.

Specification of Letters Patent. Patented Nov. 30, 1920.

Application filed July 22, 1920. Serial No. 398,271.

To all whom it may concern:

Be it known that we, CHARLES BURTON, a subject of the King of Great Britain and Ireland, residing at Goodhope street, Paddington, in the State of New South Wales, Commonwealth of Australia, mechanic, and REGINALD ALBERT SHAW, a subject of the King of Great Britain and Ireland, residing at "Warrimoo," Oliver Road, Roseville, in the State aforesaid, architect, have invented certain new and useful Improvements in Folding Beds, of which the following is a specification.

This invention has for its main object the provision of a bedstead with attached wire mattress which when not required for use may be folded into a particularly small compass, thus economizing floor space, and also enabling the bedstead to be moved with comparative ease from one place to another without being dismantled. Another and correlated object is to provide a bedstead of the nature referred to, which may be folded without removal of the stuffed mattress and bedding and without those articles requiring to be strapped on or otherwise secured. A third object of the invention is the production of a bedstead in which the wire mattress is automatically tensioned when the bedstead is extended and automatically relaxed when folded. A fourth object of the invention is a bedstead which is foldable from either end. A further object of the invention is a bedstead of the nature referred to, in which the head and foot frames are maintained in parallel planes under all conditions.

With these objects the invention consists firstly in a bedstead comprising head and foot members and side-rails, each of the latter being in two sections of equal length mutually hinged at their meeting ends and at their other ends pivoted to the head and foot frames respectively or to brackets thereon, the articulate side-rails thus formed being capable of being flexed upwardly and permitting the head and foot frames to be brought into comparatively close proximity. At the same time the wire mattress is also upwardly flexed, said mattress not being supported on a frame as is usual but suspended between transverse stretchers movable with the head and foot members.

The invention also consists in so mounting the transverse stretchers for the wire mattress that the straightening of the side-rails when extending the bedstead, tensions the wire mattress, while the flexing of the side-rails relaxes said tension and permits the mattress to flex without undue strain.

The invention further consists in the provision of a centrally disposed supporting leg under each side-rail and to which the sections of same are pivoted, said legs bearing upon the floor when the bed is extended.

The invention further consists in the provision of means as hereinafter described whereby the head and foot frames are maintained in parallel planes.

The invention further consists in the provision of a winding roller and rope gear whereby the flexing of the side-rails is initiated and the head and foot frames caused to approach each other in folding the bedstead.

The invention still further consists in such other details as will be apparent from the following description of the accompanying drawings which depict bedstead construction according to this invention, and in which,

Figure 1 is a perspective view of an extended bedstead the wire mattress being only partially shown in order not to obstruct the view of parts beneath, and

Fig. 2 a side elevation.

Fig. 3 is a side elevation of the bed partly folded, and

Fig. 4 a similar view of the bed folded.

Fig. 5 is a side elevation in larger detail showing the means for maintaining parallel relationship of the head and foot frames.

The bedstead comprises head and foot frames 10 and 11 respectively to which are attached in known manner brackets 12, 12. The side-rails each consist of sections 13 and 14 pivoted at 15, 15. to the respective brackets 12, 12. and at their meeting ends downwardly curved and at 16 pivoted mutually and to a vertical leg 17. The legs 17, 17. are connected at their tops by a transverse bar 18, while at a lower elevation is a roller 19 under which take ropes 20, 20. secured at 21 to the foot frame 11, and at their other ends winding upon a roller 22 transversely disposed between the brackets 12, 12. of the head frame 10 and terminally fitted at one or both ends with a removable handle 23.

Below the side-rail sections are tie rods 24, 24, pivoted to the brackets 12, 12, and at 25 to the central legs 17, 17. Each tie rod is of equal effective length to its corresponding side-rail section, and the distance between the pivotal points 25 and 16 is equal to the distance between the pivotal points of said tie rods and side-rail sections on the brackets 12, 12. Each side-rail section, corresponding tie rod, leg 17 and bracket 12 thus constitute in effect a parallelogram, and the four parallelograms so formed are of equal proportions.

By rotating the roller 22 in a direction to wind up the ropes 20, 20, an upward strain is put upon roller 19, the first effect being to upwardly flex the side-rails and cause the foot frame to approach the head frame. When the side rails have sufficiently flexed and the roller 19 has risen sufficiently for the ropes 20, 20, to assume a straight line no further upward pressure is exerted on said roller 19. Further closure of the bedstead is now continued by turning the roller 22, the direct pull of the ropes drawing the end frames together into the position shown in Fig. 4. It is however to be distinctly understood that rope gear and rollers are not an essential feature of the invention, as if the side rails are initially flexed by manual effort, the foot frame may afterward be pushed toward the head frame and the complete closure effected in that manner.

It is also to be understood, although reference has been made to the foot frame as the movable one, while the other is fixed, that either or both frames may be movable, and any suitable known means such as chocks, brackets, hooks or the like engaging any appropriate and convenient fixture may be employed to secure that frame which it is not desired shall move.

For the proper and smooth working of the bedstead it is desirable that the head and foot frames should be maintained at all times in parallel relationship. When the bedstead is extended, this is effected by the side-rails and tie-rods 24, 24, but when these latter elements are not in straight line position, the angles between the side-rail sections and the central leg should be equal at all times but not constant. To maintain this equality of angles, the mechanism most clearly illustrated in Fig. 5 is employed on each side of the bedstead. This mechanism comprises a slide-plate 26 slidable in a guide 27 affixed to the leg 17, said slide plate having a slot 28 which embraces pivot pin 25, and a pair of oppositely disposed links 29, 29, of equal length pivoted to said slide plate and respectively to the side-rail sections 13 and 14. As the side-rails flex, the slide plate moves longitudinally toward the foot of leg 17, and the links 29, 29, being

equal length maintain equality of the angles 65 between the leg 17 and side-rail sections 14 and 13, and insure the maintenance of parallel relationship between the head frame, foot frame and legs 17, 17.

The wire mattress 30 is secured at each 70 end to transverse stretchers 31, 31, attached by eyebolts 32, 32, to bell-crank levers 33, 33, pivoted in brackets 12, 12. The other ends of said bell-crank levers are (when the bedstead is extended) engaged by and upwardly pressed by the overhanging ends 75 34, 34, of the side-rail sections, the stretchers 31, 31, being moved toward the head and foot frames respectively, and the wire mattress thus tensioned. When however the side-rails are flexed, the pressure of the side-rail sections on said bell-crank levers is released and the tension on the mattress 80 relaxed, thus permitting the latter to curve easily over the flexed side rails as shown in Fig. 4, and also relieving it of strain when not in use.

As shown in Fig. 4 a stuffed mattress 36 need not be removed when folding the bedstead, as same together with other bedding, i. e. sheets and blankets, may be folded and accommodated within the folded bed.

What we claim and desire to secure by Letters Patent is:—

1. In a bedstead comprising head and foot frames, articulate side rails and a supporting leg under each side rail, a mattress attached at each end to transverse stretchers carried on cranked levers pivoted on the brackets attached to the head and foot frames, said levers being so disposed and arranged that when the bed is extended the side-rails contact with said levers and actuate them to tension said mattress, said tension being relaxed when the side-rails are flexed.

2. In a folding bedstead of the type wherein each side-rail is in two sections mutually pivoted at their meeting ends to a central leg and at their other ends to the head and foot frames respectively, said side-rails being capable of flexing upwardly and permitting the head and foot frames to be brought into close proximity, means for 110 maintaining said frames and central legs in parallel relation; said means comprising at each side of the bedstead a slide running parallel to the length of the central leg and in guides thereon, and a pair of links of 115 equal length pivoted to said slide and at their other ends individually pivoted to the rail sections, substantially as herein described and illustrated.

3. In a bedstead comprising head and foot frames articulate side rails and a supporting leg under each side rail, means for initiating the upward flexing of the rail sec-

tions and for folding the bed, comprising a winding drum rotatably mounted at one end of the bedstead, means for rotating said drum, a flexible connection between said drum and the other end of the bedstead; and
5 a guide roller supported between the central legs which support the side rail section, said

flexible connection taking under said guide roller which is at a lower elevation than the ends of said connection.

10

Signed at Sydney, this fifteenth day of June, A. D. 1920.

CHARLES BURTON.
REGINALD ALBERT SHAW.
